DUST FLOW INDICATOR FOR SUCTION
CLEANING DEVICES

Daniel Benson Replogle, deceased, late of Berkeley, Calif., by Bank of America National Trust & Savings Association, San Francisco, Calif., Carl S. Replogle, Piedmont, Harold E. Queen, Berkeley, and Laurie H. Bullock, Berkeley, Calif., executors, assignors to The Ohio Citizens Trust Company, Toledo, Ohio, a corporation of Ohio, as trustee

Original application April 9, 1941, Serial No. 387,717. Divided and this application November 18, 1943, Serial No. 510,811

3 Claims. (Cl. 302—65)

The invention relates to cleaning devices for airplanes and like moving vehicles wherein the partial vacuum created at certain portions of the vehicle while in motion is utilized for the operation of suction cleaning appliances of any suitable description.

On account of the great increase in air travel, particularly between the tropics and northern climates, there is now an urgent need on the part of the passengers for appliances which may be used for clearing their baggage, clothing, etc. of any dust, pestiferous insects or larva which may have accumulated and these same cleaning appliances may be used if desired for clearing table debris and litter of every kind.

Furthermore, in the compressed air passenger compartments of airplanes, periodical change of air is necessary and the cleaning appliances of the present invention may also be employed to assist in ventilating such compartments.

The present application is a division of my application Serial No. 387,717, filed April 9, 1941, and the claims of the present application are directed particularly to the combined valve and dust indicator which is included in the system.

The invention will be more readily understood by reference to the accompanying drawings and the following detailed description which are intended as illustrative only and not as limiting the invention to the particular details of construction set forth therein.

In the drawings:

Fig. 1 is a view somewhat diagrammatic in character, partly in side elevation and partly in section, showing a portion of an airplane equipped with a cleaning appliance in accordance with the present invention.

Fig. 2 is a view on an enlarged scale partly in end elevation and partly in section, showing a dust indicator employed in the system, the dust deflector being directly in front of the air inlet.

Fig. 3 is a sectional view of the same showing the deflector shifted slightly to cause whirling of dust about the indicator.

Fig. 4 is an axial section through the indicator and showing its attachment to a partition wall.

Fig. 5 is a diagrammatic view of an airplane showing a modification in which a suction connection is located at the side thereof.

Fig. 6 is an enlarged detail sectional view of the same showing cleaning appliances attached to the suction connection.

Fig. 7 is a somewhat diagrammatic view partly in side elevation and partly in section showing a further modification wherein the cleaning ap-

paratus is connected to a rear compartment of the plane.

Fig. 8 is an enlarged detail showing a valve for closing the suction connection when the cleaning appliance is not in use.

Referring to the drawings and with particular reference to Fig. 1, the numeral 10 denotes a portion of the fuselage of an airplane of any suitable type. When the plane is in motion being driven by means of its propellers, the forward motion of the ship tends to produce a condition of increased pressure at the forward portion of the ship and a condition of reduced pressure toward the rear end thereof. This reduced pressure or partial vacuum is utilized according to my invention to operate suction cleaning appliances, no separate source of power being required for the operation of such devices.

The reference character 11 denotes a passenger compartment which is generally filled with air under pressure somewhat greater than the normal atmospheric pressure, such pressure being maintained in any suitable manner as by providing ventilating means at the forward or pressure portion of the plane. Such means do not constitute any portion of the present invention and are not specifically disclosed herein, since they are well known in the art.

At 12 there is indicated a wall or partition separating the passenger compartment 11 from the rear portion of the plane. Extending rearwardly from the partition 12 toward the tail of the plane is a passage 13 which extends to the tail portion of the plane at which a partial vacuum is created when the plane is in motion. This passageway may extend indefinitely through a hollow brace to the tail of the fuselage, that is, the same tube that carries the suction may be a hollow brace, being a component part of the fuselage of the plane.

Connected to the forward end of the suction passage 13 through a dust indicator or the like A is a flexible hose 15 connected to a wand-like suction pipe 16 which may be of hard fiber or any suitable material and which is provided with a suction nozzle or floor tool 17 at the end thereof. The hose pipe 15 is preferably long enough so that the nozzle 17 will reach any portion of the compartment 11 which it is desired to clean. A suitable extension device may be employed if desired and the nozzle or floor tool 17 may be substituted by any other form of nozzle as is well known in the cleaner art. The upper curved portion of wand 16 may function as a handle for

moving the appliance over the floor or other surface to be cleaned.

The indicator A serves the dual purpose of disclosing the quantity of dust being drawn through the system and of providing a valve for opening or closing communication between the passenger compartment and the rear of the plane. Thus, this valve serves also as a ventilating means. As shown the indicator includes a cylindrical casing 20 suitably secured to the partition 12 as indicated in Figs. 1 and 4 and is provided with an opening 21 communicating through an opening in the partition 12 with the suction passage 13. The casing is also provided with an inlet opening 22 communicating with a short pipe 23 over which the end of hose 15 is adapted to be fitted.

Revolvably fitted within the casing 20 is an inner cylindrical valve member 24 having a dome shaped transparent top 25 which may be formed of glass, Celluloid, or transparent plastic material such as vinyl resin or the like. The rotatable valve is provided with a flange 26 which is turned over a flange on the top member 25 and serves to hold the same in place. This flange also provides a finger grip for rotating the valve. The valve member is provided with an opening 27 which may be brought into registry with the opening 22 or may be rotated to shut off communication between the front and rear portions of the partition 12.

Extending upwardly part-way across the opening 27 is a deflector 28 preferably formed integral with the valve member 24 which may be brought directly into the path of the dust laden air entering through the inlet passage 23 or may be moved slightly to one direction or the other so as to cause whirling of the dust either in a clockwise or a counter-clockwise direction depending on the direction of rotation, as set forth in my application Serial No. 381,200, filed February 28, 1941, entitled Dust flow indicator for suction cleaning devices, now Patent No. 2,269,483, dated January 13, 1942. A suitable screen 29 may be placed across the opening 21 leading to the pipe 13 if desired.

Instead of having the passage 13 extend to the tail of the plane as indicated in Fig. 1, a valve 30 may be provided at one side of the fuselage at a point where partial vacuum exists. A fitting 31 may be provided communicating with this valve as indicated in Fig. 7 and a flexible hose 32 may be attached at one end to such fitting and at its other end attached to a pipe 33 comprising a tubular handle which communicates with the outlet of an indicator A'. A wand-like suction pipe 34 is connected to the inlet pipe of the indicator and may be provided with any suitable suction tool not shown. The hose is sufficiently long to permit movement of the appliances to any part of the interior of the plane. The construction of the indicator A' may be similar to that shown at A in Figs. 1 to 4 inclusive, or may be of the type disclosed in my above mentioned patent. The general function of both indicators is the same. The curved pipe 33 may be used to move the cleaning device back and forth across the surface to be cleaned.

In the construction shown in Figs. 7 and 8 a fluid-tight partition 35 is provided at the rear separating the suction compartment 36 from the forward portion 50 of the plane. The compartment 36 may be opened to atmosphere and the partition 35 is provided with a flap valve 37 covering an opening 38. A nipple 39 at one end of the cylindrical casing 40 is inserted in the open-

ing 38 when the valve 37 is raised and this casing is provided with a suitable transparent top 41. If desired the top 41 may be formed as a valve as in the construction shown in Figs. 1 to 4. Where filtering is desired a suitable screen 42 similar to the screen 29 may be employed. A flexible pipe 43 is connected to the transparent top 41 and is connected at its other end to a wand such as is shown at 34 in Fig. 6 or a tubular member 16 such as is shown in Fig. 1, either of which may be equipped with any suitable floor cleaning tool. Where the suction pipe discharges directly to the outside of the plane the filter or screen may be omitted if desired. However, such filter performs the usual function of preventing loss of valuable articles which may be drawn into the nozzle of the suction cleaner by mistake and would otherwise be discharged to the atmosphere.

The operation of the various forms of cleaning apparatus herein set forth will be apparent from the foregoing description. As the plane is traveling forward by rotation of its propellers a partial vacuum is created toward the rear portion thereof and any suction pipe connected to a location where reduced pressure exists may be used in the operation of various forms of cleaning apparatus. The indicator A or A' serves to inform the operator of the quantity of dust which is being drawn into the apparatus. It may be noted that dust passing through a transparent passage is not readily observable when traveling at the rate usual in the operation of suction cleaners, and an enlarged chamber such as is provided by the indicator A and A' has the effect of slowing the motion even in the neutral position of the deflector (Fig. 2) and therefore rendering the dust visible, but such dust is rendered more visible by eddying and causing it to re-travel many times in the same path as is the case where the deflector is angularly removed from the direct path as indicated in Fig. 3.

If desired a suitable barometer B (Fig. 1) may be employed to show fluctuations in difference between the inside and outside atmospheric pressures, since the cleaning apparatus is only operable when a considerable degree of difference exists.

The invention has been described in detail for the purpose of illustration but it will be apparent that variations and modifications may be resorted to without departing from the spirit of the invention.

We claim:

1. In an air-method cleaning system, including a series of tubular elements connecting zones of different pressures, a dust indicator interposed between a pair of successive tubular elements comprising a coupling element having inlet and outlet pipes, a rotatable member having a transparent window, and deflecting means carried by said rotatable member and adapted to be positioned adjacent said inlet opening for the purpose of directing air and dust onto the window, said deflector being movable to various angular positions with reference to the inlet opening for the purpose of causing whirling movement in either direction within the indicator.

2. In a suction cleaning system, a dust indicator comprising a cylindrical chamber having an inlet for dust laden air in the cylindrical wall of the chamber and an outlet opening at the bottom thereof, a transparent window located opposite the outlet opening, deflecting means located adjacent the inlet opening adapted to direct air and dust onto the window, and means

for angularly adjusting said deflecting means to cause whirling movement of the air about the axis of the cylindrical chamber, said adjusting means including a rotatable cylindrical valve member fitting within the cylindrical wall of said chamber, said window serving as a cover for said valve member, and said deflecting means being carried thereby.

3. In a suction cleaning system, a dust indicator comprising a cylindrical chamber having an inlet for dust laden air in the cylindrical wall of the chamber, and an outlet opening at the bottom thereof, a transparent window closing the top of the chamber, means located adjacent the inlet opening for deflecting the incoming dust and air toward said window prior to passing through the

outlet, said means being adjustable to cause a whirling movement in a clockwise or counter-clockwise direction, and a rotatable cylindrical valve member fitting within the cylindrical wall of said chamber, said transparent window constituting the cover for said rotatable cylindrical member, and said deflector being carried thereby.
